UNITED STATES PATENT OFFICE.

CONRAD DAHL, OF CHICAGO, ILLINOIS, ASSIGNOR TO ROBERT N. BURTON, OF CHICAGO, ILLINOIS.

GLIDER KITE.

Application filed May 5, 1923. Serial No. 636,823.

To all whom it may concern:

Be it known that I, CONRAD DAHL, a citizen of the United States, residing at Chicago, in the county of Cook and State of Illinois, have invented certain new and useful Improvements in Glider Kites, of which the following is a specification, reference being had to the accompanying drawings, forming a part thereof.

10 The purpose of this invention is to provide an improved kite construction which shall be comparatively simple to produce and which shall have a steadiness and certainty of control not hitherto attained. It

15 consists of various features and elements of construction in combination as herein described and shown in the drawings and as indicated by the claims.

In the drawings:—

20 Figure 1 is a face or bottom plan view showing the under side of the kite.

Figure 2 is an end elevation looking in the direction of the arrow, 2, on Figure 1.

Figure 3 is a side elevation showing the 25 kite approximately in the position of flight.

Figure 4 is a detail perspective view of certain parts of the frame.

Figure 5 is a perspective view illustrating the assembled relation of the parts shown in 30 Figure 4.

Figure 6 is a transverse section taken as indicated at line 6—6 on Figure 1.

Figure 7 is a detail perspective of a fastening tab or lug for the main sail.

35 In the construction illustrated the main sail, 1, is of the conventional four-sided shape having its two shorter sides, *a*, forming an obtuse angle and its two longer sides, *b*, forming an acute angle at the opposite end of the sail. The frame structure on

40 which the sail is mounted comprises a mid-rib, 2, and a cross-arm, 3, the latter extending for some distance at each end beyond the lateral corners, *c*, of the sail, 1. A firm

45 joint between the mid-rib, 2, and the cross-arm, 3, may be made at their intersection as indicated in Figures 4 and 5 by forming the cross-arm with a pair of spaced lugs, 4, between which the mid-rib, 2, is lodged with

50 a single lug, 5, extending past one side of the cross-arm, 3,—the assembly being firmly

55 bound in position by a string or wire, 6. In the vicinity of the acute end of the sail, 1, an upstanding post or strut, 7, rises from the mid-rib, 2, to support a second cross-

arm 8, which is equal in length to the arm, 3, and extends parallel to it in a plane above that of the main sail, 1. Stretched between the end portions of the arms, 3 and 8, are a pair of inclined wings or elevating planes, 9, whose lateral edges, 10, are re-enforced with strips of cloth or paper and whose ends are lapped around the cross-arms at 11, as indicated in Figure 3. The strut, 7, is held upright by the tension of the wings 9, opposed by the tension of guys, 12, which extend from the arm, 8, at the rear inner corners of the wings, 9, to a point on the rearwardly extending mid-rib, 2, near its end.

Substantially at the point on the mid-rib, 2, at which the guys 12, are anchored, a second strut or upright 13, rises from the mid-rib preferably to a height about equal to that of the strut, 7, for supporting a short cross-arm, 14, which is laterally stayed by guys, 15. Triangular tail planes, 16, diverge upwardly from the mid-rib, 2, forming an upwardly open V-shaped body

which extends from the rear corner or apex of the main sail, 1, to the cross-arm, 14, the oblique edges, 17, of the plane, 16, being preferably re-enforced and folded upon strings, 18, which are secured to the cross-arm, 14, as indicated in Figure 3. The strut, 13, is thus held upright by the tension in the strings, 18, balanced by rearward and downwardly trending guys, 19,

which converge at a screweye, 20, near the extreme end of the mid-rib, 2. Similarly the strings, 18, may be attached to a screw-eye, 21, in the lower side of the rib, 2. The string, 22, by which the kite is held in flight branches at a point 23, below the main sail, 1, one line, 24, extending to the screweye, 21, and a short line, 25, extending at about right angles to the middle of an equalizer, 26, from whose opposite ends the strings, 27, diverge to screweyes, 28, placed in the forward cross-arm, 3, at equal distances from its mid-point where it joins the rib, 2.

90 A good method of attaching the main sail, 1, to the frame consists in using gummed cloth or paper lugs or tabs, 29, like that shown in Figure 7 folded at one end about a cross-arm or stick, 30, about which a string, 31, is tied at the middle. The tabs, 29, are glued to the surface of the sail, 1, near its corners with the cross-sticks, 30, outward so the strings, 31, may lead therefrom to screw-eyes, 32, 33 and 21, for securement.

In the structure as described, it will be seen that I provide a main sail, 1, from whose corners *c*, the wings or elevators, 9, rise obliquely for pocketing the wind and using its force to impel the kite forward in such a direction that the main sail, 1, operates as a gliding plane extending approximately in the direction of travel. The V-shaped body formed by the tail planes, 16, serves to spread the wind toward the elevators, 9, and at the same time to steady the kite laterally so that in flight its motion is smooth and definitely directed without any of the pitching and diving which is characteristic of so many kite structures especially in a strong wind. Another feature which contributes to steadiness and prevents the kite from pitching or diving in response to sudden gusts of wind is the flexibility of the end portions of the cross-arm, 8, and of the rear portion of the mid-rib, 2. As indicated in dotted lines in Figure 1, the wings or elevator, 9, being attached to parts of the arm, 8, beyond the guys, 12, will flex the cross-arm as they fill and swell under the wind pressure, the outer edges of these wings, 9, tending to be more curved than the inner edges as indicated in Figure 3. At the same time the tension of the wings, 9, as they are thus curved tends to tip the strut, 7, forward as shown in Figure 3 and this movement of the parts being transmitted through the guys, 12, tends to bend up the rear end portion of the mid-rib, 2, as also indicated in dotted lines in Figure 3. This flexing and yielding of the parts in response to the wind pressure exerted against the elevator planes, 9, tends to cushion the effect of sudden changes in pressure and prevent the kite from responding bodily thereto with the result that the kite as a whole moves steadily and smoothly and maintains its general position quite definitely at all times.

45 I claim:—

1. In a kite, the combination of a single main sail and a pair of elevator planes extending divergently rearward at an acute angle from the plane of said sail at opposite sides of its longitudinal center line, and beyond its lateral edges.
2. In a kite, the combination of a longitudinal mid-rib, a cross-arm secured thereto, a single main sail lying substantially in the common plane of the mid-rib and cross-arm and a pair of elevator planes each extending from the cross-arm at opposite sides of the mid-rib and diverging rearwardly at an acute angle from the plane of the sail.
3. In a kite, the combination of a longitudinal mid-rib, a cross-arm secured thereto near the forward end, a main sail supported by said mid-rib and cross-arm substantially in the common plane of said parts, a second cross-arm extending parallel to the first and

parallel to the plane of the main sail spaced away from the latter, and an elevator plane stretched between said cross-arms at an acute angle to the plane of the main sail.

4. In a kite, the combination of a longitudinal mid-rib, a cross-arm secured thereto, a main sail supported substantially in the plane of the mid-rib and cross-arm, a second cross-arm positioned rearwardly of the first in parallel relation thereto and parallel to the plane of the main sail but spaced from the mid-rib, and a pair of elevator planes extending respectively from the outer end portions of the first cross-arm to the second cross-arm forming acute angles with the plane of the main sail.

5. In the combination defined in claim 4, a strut supporting said second cross-arm in spaced relation to the mid-rib and guys extending rearwardly from said cross-arm toward the rear end of the mid-rib.

6. In the combination defined in claim 4, the second cross-arm being flexible and adapted to yield at its end portions under tension of the elevator planes.

7. In the combination defined in claim 4, means supporting said second cross-arm in spaced relation to the mid-rib with guys extending rearwardly from said cross-arm attached to the rear portion of the mid-rib, the latter being adapted to flex under tension of the guys in response to the swelling of the elevator planes.

8. In a kite, the combination of a main sail with a mid-rib extended rearwardly beyond the sail, and a transverse plane supported by said rearwardly-extending portion of the rib to steady the kite; a strut up-standing from said rear portion of the mid-rib to support the upper corners of said transverse plane, said plane comprising two dihedrally disposed triangular wing sections with their common edge extending along the mid-rib, and its forward apex substantially adjoining the rear portion of the main sail.

9. In the combination defined in claim 8, said steadyng planes being triangular in form widening rearwardly with a cross-arm and a strut supporting said cross-arm from the rear portion of the mid-rib at a distance above the latter for attachment of the upper rear corners of said steadyng planes thereto and guys extending downward and rearwardly from said cross-arm to the extreme end portion of the mid-rib.

10. In a kite, the combination of a main sail, a longitudinal mid-rib and a forward cross-arm supporting said sail and lying substantially in its plane, the cross-arm having end portions extending beyond the sail, and a pair of elevator planes attached to said extending portions of the cross-arm diverging rearwardly at an acute angle from the plane of the main sail.

11. In the combination defined in claim 130

10, a second cross-arm and means supporting it from the mid-rib in spaced relation thereto and parallel to the first cross-arm, said elevator planes being stretched between
5 the first and second cross-arms.

12. In a kite, the combination of a main sail, a longitudinal mid-rib and a cross-arm, a holding string branched at a point below the main sail with one branch extending
10 rearwardly for attachment to the mid-rib, the other branch extending forwardly a short distance to a transverse equalizer bar and two strings extending from the ends of said equalizer divergently forward to points of
15 attachment on the cross-arm at opposite sides of the mid-rib.

13. In the combination defined in claim 12, a pair of elevator planes diverging rearwardly at an acute angle from the plane of said main sail at opposite sides of the mid-rib and attached to opposite ends respectively of the cross-arm, means supporting the rear ends of said planes at a distance above the main sail and transverse steady-²⁰ing planes extending upwardly from the mid-rib at a portion thereof which extends rearwardly from the main sail, said first branch of the string being attached to the mid-rib at a point forward of said steady-²⁵ing planes.

CONRAD DAHL.
